US0D1073593S

(12) **United States Design Patent** (10) **Patent No.:** **US D1,073,593 S**
(45) **Date of Patent:** **** May 6, 2025**

(54) **BATTERY**

(71) Applicant: **MOTOROLA SOLUTIONS, INC.**,
Chicago, IL (US)

(72) Inventors: **Goktug Duman**, Oakland Park, FL
(US); **William Robertson**, Plantation,
FL (US); **Ryan M Nilsen**, Plantation,
FL (US)

(73) Assignee: **MOTOROLA SOLUTIONS, INC.**,
Chicago, IL (US)

(**) Term: **15 Years**

(21) Appl. No.: **29/858,586**

(22) Filed: **Nov. 2, 2022**

(51) LOC (15) Cl. **13-02**

(52) U.S. Cl.

USPC **D13/103**

(58) **Field of Classification Search**

USPC D13/103, 107, 108, 110, 118, 119, 184,
D13/199, 112; D24/111; D14/251, 434

CPC H02J 7/0042; H02J 7/0044; H02J 7/0054;
H02J 7/00

(57) **CLAIM**

The ornamental design for a battery as shown and described.

DESCRIPTION

FIG. 1 is a front perspective view of an ornamental design for a battery;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines illustrate portions of the battery that form no part of the claimed design.
